AUTOMOBILE

Edward L. Weed, 42 Carter St., Providence, R.I.

Filed Oct. 15, 1959, Ser. No. 57,939

Term of patent 3½ years

(Cl. D14—27)

FIG. 2

FIG. 3

FIG. 1.

FIG. 1 is a perspective view of an automobile showing my new design;

FIG. 2 is a side elevational view thereof; and

FIG. 3 is a sectional view taken on the lines 3—3 of FIG. 1.

The dominant features of the design reside in the portions shown in full lines. Portions of the automobile are omitted in FIG. 2 for convenience of illustration.

I claim:

The ornamental design for an automobile, substantially as shown and described.
